UNITED STATES PATENT OFFICE.

EMIL GRAF, OF NEW YORK, N. Y., ASSIGNOR TO RUDOLPH STEINACHER, OF NEW YORK, N. Y.

SPARK PLUG.

Application filed September 14, 1922. Serial No. 588,136.

To all whom it may concern:

Be it known that I, EMIL GRAF, a citizen of the Republic of Switzerland, residing at New York, county of New York, and State 5 of New York, have invented certain new and useful Improvements in Spark Plugs, of which the following is a specification.

One of the principal objects of this invention is to provide in a spark plug for 10 use upon an internal combustion engine, an air gap or intensifier arranged within the plug and forming an integral part thereof.

Another object is to arrange the gap in the upper part of the plug and to provide 15 means for the ready observation of the passage of a spark across the gap.

A further object is to construct the observation means so as it may be placed in an open or closed position.

20 Another object is to provide means for varying the intensifying gap so as to short circuit the plug when it is desired to test the firing of any particular cylinder or cylinders.

25 For the accomplishment of these and such further objects as will hereinafter be apparent to those skilled in the art to which this appertains the invention consists in the construction, combination and arrangement 30 of parts herein specifically described and illustrated in the accompanying drawings, wherein is shown a preferred embodiment of the invention, but it is to be understood that changes, variations and modifications 35 may be resorted to which fall within the scope of the claims hereunto appended.

In the drawings forming a portion of this specification:

Fig. 1 is a central sectional view through 40 a spark plug embodying my invention.

Fig. 2 is a side view of the top portion of a plug showing a modified form of the means for opening or closing the observation openings.

45 Figs. 3 and 4 are views similar to Fig. 2 of a further modification of the opening or closing means.

Fig. 5 is a horizontal section on the line 5-5 of Fig. 1.

50 As shown in the drawings, a hollow metallic base 10 is provided with the threaded extremity 11 and the shoulder 12 adapted

to be engaged with the engine cylinder in the usual and well known manner. The base 10 carries the electrode 13 spaced from 55 an electrode 14 to provide the usual spark gap, the electrode 14 being suitably secured within an insulating block 15, preferably of fibre, as by the bushing 16, which is forced upon the electrode 14 and is screwed 60 within one of the cup shaped recesses 17 formed in the extremities of the insulating block 15. Intermediate its ends the insulating block is provided with a projecting shoulder 18, which is adapted to be clamped 65 between a shoulder 19 provided on the inner bore of the base 10, and the lower end of a top piece 20, which is screwed on the upper end of the base, suitable gaskets 21 being provided to insure a tight joint. 70

It will be noted that the ends of the insulating block are equidistant from the shoulders 21 and the electrode 14 projects from the insulating block an equal distance 75 at each end, instead of passing entirely through the block, for a purpose which will hereinafter appear.

The top piece 20 is a hollow member having an annular shell like portion or casting 80 23 projecting upwardly from the enlarged shoulder 24 and which portion is preferably provided with any suitable number of apertures 25. The lower inner wall of the top piece may be provided with a shoulder 26 against which may be seated 85 the lower end of a sleeve 27 preferably of metal which is frictionally engaged within the shell portion 23.

The sleeve 27 is preferably provided with a horizontally extending slot 50 having the 90 recesses 51 at its ends, and the shell like portion 23 is provided with a resilient struck out tongue 52 having its inner end turned inwardly as at 53 to engage within the recesses 51, the relative positions of the 95 recesses and tongue being arranged to hold the sleeve 27 with its apertures 27^a in or out of alignment with the apertures 25 and also to hold the sleeve longitudinally in the position of maximum efficiency of the air 100 gap to be hereinafter described. The sleeve 27 is also provided with a longitudinally extending slot 55 which leads from one of the recesses 51 to the lower edge of the sleeve to

permit longitudinal outward movement of the top piece.

The upper end of the sleeve 27 is counter-bored as at 28 to provide a shoulder in which is seated an upper insulating block 29 having a flanged shoulder 30 at its lower end about which the upper edge of the sleeve 27 is spun to secure the block 29 and sleeve 27 together. An electrode 31 of suitable 10 conducting material passes through the block 29 and its lower end terminates a short distance from the upper end of the electrode 14 to provide an intensifying gap which is located substantially in horizontal 15 alignment with the apertures 25. The upper end of the electrode 31 is provided with the usual threaded end upon which the customary binding nut 32 is screwed.

The operation of the plug described above 20 is as follows: In the ordinary operation of the plug the insulating block 29 and sleeve 27 will be turned to close the apertures 25 as will be readily understood. If it is desired to observe the conditions under which 25 the ignition system is working, the block and sleeve are partially rotated to bring the apertures 27^a into register with the apertures 25. As it will be obvious that a spark may pass across the intensifying gap but 30 its passage across the lower gap may be prevented by carbon deposit upon the terminals of the electrodes 13 and 14, the insulating block 29 and sleeve 27 may be slid longitudinally to increase the gap between 35 the electrodes 14 and 31, thereby causing the plug to be short circuited, the spark jumping across from the electrode 31 to the sleeve 27. The tongue 52 may be slid through the slot 55, when the parts are 40 moved longitudinally. If desired the struck out tongue 52, horizontal slot 50 and recesses 51, may be dispensed with and the upper and lower parts of the plug may be held 45 together by frictional contact between the sleeve 23 and the sleeve 27, such frictional contact being sufficient to resist the vibration of the machine. It will thus be seen that a plug constructed as shown in Fig. 1 50 will embody an intensifier and an ignition testing device combined in a unitary structure with the plug.

In the form shown in Fig. 2, the construction is similar to that shown in Fig. 1, except that the shell portion 23^a is provided 55 adjacent its upper end with an inwardly projecting flange 40 which prevents longitudinal movement of the insulating block 29 and sleeve 27, but permits rotation of the block and sleeve to open and close the apertures 25, and 27^a. In Fig. 3 the block 29 is 60 secured directly to the shell portion 23^a by spinning the upper end of the shell portion over the projecting shoulder 30 of the block, and a sleeve 41 provided with the 65 apertures 42 is frictionally mounted over

the shell portion 23^a. In both of these forms means similar to the tongue 52 and slot 50 may be provided. In Fig. 4 the upper end of the sleeve 23^b is threaded to engage the knurled nut 43, by means of which the block 29 is held in place and a collar 44 is slidably mounted on the outside of the sleeve 23^b, the width of the collar being substantially half the distance between the nut portion 45 of the shell and the knurled 70 nut 43. The apertures 25 in this form are opened and closed by sliding the collar 44 longitudinally of the plug.

Having thus described my invention, what I claim as new and desire to secure by Letters Patent, is:

1. A spark plug comprising a base, a top piece having a shell like casing, an insulating block and sleeve slidably carried by said casing for longitudinal or rotatable movement, an electrode carried by said base, a second electrode carried by said block and spaced from said first named electrode within said casing to provide an air gap, and said casing and sleeve provided with a plurality of apertures adapted to be moved into or out of registry by the rotatable movement of said sleeve. 85

2. A spark plug comprising a base, a top piece having a shell like casing, an insulating block and sleeve slidably carried by said casing for longitudinal or rotatable movement, an electrode carried by said base, a second electrode carried by said block and spaced from said first named electrode within said casing to provide an air gap, and said casing and sleeve provided with a plurality of apertures adapted to be moved into or out of registry by the rotatable movement of said sleeve and means to retain said sleeve with said apertures in 90 opened or closed positions. 95

3. A spark plug comprising a base, a top piece having a shell like casing, an insulating block and sleeve slidably carried by said casing for longitudinal or rotatable movement, an electrode carried by said base, a second electrode carried by said block and spaced from said first named electrode within said casing to provide an air gap, and said casing and sleeve provided with a plurality of apertures adapted to be moved into or out of registry by the rotatable movement of said sleeve and said sleeve adapted to increase said air gap and short circuit said plug when it is moved longitudinally. 110

4. A spark plug comprising a base, a top piece having a shell like casing, an insulating block and sleeve slidably carried by said casing for longitudinal or rotatable movement, an electrode carried by said base, a second electrode carried by said block and spaced from said first named electrode within said casing to provide an air gap, 115

and said casing and sleeve provided with a plurality of apertures adapted to be moved into or out of registry by the rotatable movement of said sleeve, said sleeve adapted to increase said air gap and short circuit said plug when it is moved longitudinally, and means to retain said sleeve with said apertures in opened or closed position and to retain said sleeve with said air gap in normal operative position. In testimony whereof I have affixed my signature.
